UNITED STATES PATENT OFFICE
DEVICE FOR REGULATING PRESSURE IN
MACHINE ROLLERS
George Babicz, Chicago, Ill.
Application April 29, 1943, Serial No. 484,997
2 Claims. (Cl. 101—351)

Broadly the present invention relates to means for regulating, that is for increasing or decreasing, the pressure between a plurality of rollers in various types of machines.

More specifically the present invention relates to the printing machines and has for its object the provision of a device whereby the pressure between fountain roller and ink spreading roller may be regulated with the greatest degree of accuracy and precision.

A still further object of the present invention is the provision of means in a printing machine to bodily move the fountain roller to or away from the printing roller thereby increasing or decreasing the pressure therebetween and as a consequence transferring lesser or larger amount of ink, as may be desirable, from the fountain roller to the printing roller.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views

Fig. 1 is a cross-sectional view on a vertical plane through a plurality of shafts, supporting a plurality of rollers, with rollers shown in elevation and in a cooperating position;

Fig. 2 is a side elevational view of the present device and transversely of roller-supporting shafts; and

Fig. 3 is an end view of a pair of shaft-supporting and pressure regulating devices, one being shown in elevation and the other in cross-section.

Referring in detail to the present drawing, the same illustrates a relative juxtaposition of a plurality of rollers, including a fountain roller 10, which is partly immersed in ink 11 contained in trough 12. Roller 10 is set upon shaft 13. Ink spreading roller 14 set upon shaft 15 is in a horizontal relative position with roller 10 and contacts therewith for the purpose of wiping off the excess ink upon roller 10 and uniformly spreading the same thereupon so that fountain roller 10 may transfer a uniform film of ink upon printing roller 16 which remains above roller 10 and slightly to one side thereof. Compression roller 17 contacts with printing roller 16 and is disposed directly above it. The latter two rollers are set upon shafts 18 and 19, respectively. Rollers 10,

14, 16 and 17 rotate into the directions indicated by arrows in Fig. 1. Roller 16 is adapted to carry upon its periphery printing impressions which, when inked by roller 10, are transferred upon the paper when the same is fed and moves between said rollers 16 and 17.

It is desirable to regulate the pressure between rollers 10 and 14 in order to regulate the ink film upon roller 10 for the purpose of transferring ink therefrom to roller 16 in a lesser or larger degree, as may be desirable and dependent upon the various factors, such as the quality of paper which is being printed or the nature, quality of consistency of the ink in trough 12. This object is accomplished by means of a pressure regulating device, each set upon standards 20, which directly carry shafts 18 and 19. This device includes a pair of spaced guiding rails 21 set upon the inner faces of standards 20 and disposed transversely thereof, with one ends projecting beyond the adjacent marginal edge of standards 20. Said rails are affixed to standards 20 by means of screws 22, and constitute guiding means for plate 23, one receivable within each pair of said guiding rails 21. One end of plate 23 is cut out longitudinally and centrally thereof for defining slot 24, with the resultant pair of edge bars 25.

To prevent lateral shifting of plate 23 and bars 25, both are grooved as at 26 to receive therewithin correspondingly shaped flanges 27, by virtue of which arrangement plate 23 and bars 25 are retained within guiding rails 21, but are permitted to make longitudinal sliding movement.

Bearings 28, which support shaft 15 at both of its ends, are set within slots 24 and between bars 25. At the outer ends of bearings 28 arms 29 upwardly project and are pivoted for angular shifting movement upon pivots 30 carried by the upper bars 25. Arms 29 have horizontal extensions 31, the latter carrying upwardly projecting arms 32, the latter being laterally bent and having their free ends bifurcated as at 33. Journalized within said bifurcated ends 33 of arms 32, as at 34 are rods 35. The opposite ends of said rods are threaded to receive a nut lock 36. The threaded end portion of each rod 35 rests within the bifurcated end of bar 37 and is there held in an adjusted position by wing nut 38, bar 37 being affixed to the edge of plate 23 by means of screws 39. Arms 32 are laterally bent to one side so as to bring the bifurcated ends 33 directly above the adjacent guiding rail 21 and in alignment with bars 37.

The respective positions of fountain roller 10

and roller 14 is indicated by dotted lines upon Fig. 2.

Bearings 40, within which shaft 13 is set for rotation, are integrally formed with the two oppositely disposed plates 23.

Plate 23, longitudinally and centrally thereof and on its edge bordering slot 24 is provided with socket 41 to receive therewithin a coil spring 42, which bears against the side of bearing 28 and normally urges the same away from that edge of plate 23. Thus when nut lock 36 is released, that is when its contactual engagement with bar 37 is loosened, spring 42 automatically shifts bearing 28 away from bearing 40, causing angular shifting of arm 29, upon pivot 30, as well as arm 32 towards said bar 37, thereby decreasing the pressure between the two rollers 10 and 14. Thereupon wing nut 38 is adjusted so as to maintain rods 35 in a rigid adjusted position with respect to bar 37, which in turn will maintain the two rollers 10 and 14 in a rigid, relatively adjusted position. To reverse the operation and shifting of bearings 28, that is for bringing roller 14 towards roller 10 to increase the pressure therebetween, wing nut 38 is loosened, rod 35 is shifted into the opposite direction, that is away from bar 37, which operation shifts bearings 28 towards bearings 40 and against the tension of springs 42, and when the desired pressure between rollers 10 and 14 was brought about nut lock 36 is screwed upon rod 35 and towards wing nut 38 for the purpose of locking rod 35 to bar 37 in the newly adjusted relative position with respect to bar 37. This operation of rods 35 shifts bearings 28 and roller 14 towards roller 10, and against the tension of coil spring 42, and increases the pressure between said rollers.

From the hereinabove description it will be seen that the excess amount of ink taken up by roller 10 will be wiped off therefrom as the same rotates past roller 14. As the pressure between the two rollers is increased, the amount of coating of ink upon roller 10 is decreased. Ink in turn is transferred from roller 10 to the printing dies upon roller 16, to be in turn transferred to the paper passing between rollers 16 and 17 as aforesaid.

It is oftentimes desirable to regulate the pressure between fountain roller 10 and printing roller 16. For this purpose means has been provided whereby roller 10, roller 14 and plates 23 may be bodily moved on horizontal plane, for the purpose of bringing fountain roller 10 to or away from printing roller 16. This means includes a horizontal bar 43 integrally formed with and horizontally projecting from the marginal edge of each standard 20, and below the lowermost guiding rail 21. Each of said bars 43 has an upwardly projecting vertical bifurcated extension 44, which is in alinement with plate 23 and in front of its adjacent vertical edge. Screw 45 rigidly affixed to plate 23 carries nut lock 46 contacting with one face of the bifurcated end of extension 44. Wing nut 47 completes the structure. By shifting nut lock 46 and wing nut 47 away from extension 44 screw 45 may then be shifted longitudinally into one or the other direction and within the bifurcated end of extension 44, and with it plate 23 with bearings 28 and 40, rollers 14 and 10, rod 35 and bar 37, are likewise shifted. In fact when plate 23 is shifted,

rollers 10 and 14, with the entire mechanism for increasing the pressure therebetween, and hereinabove described, are likewise bodily shifted, without in any manner disturbing the contactual adjusted relation and pressure between rollers 10 and 14. As hereinabove indicated guiding rails 21 by virtue of their flanges 27 permit longitudinal sliding movement of plate 23 and bars 25, preventing however any lateral shifting thereof.

As is seen in Fig. 1 printing roller 16 remains to the side of the vertical transverse axis of inking roller 10, which juxtaposition of the two rollers makes it possible to shift inking roller 10 to or away from printing roller 16 and regulate the contactual pressure therebetween by means last hereinabove described.

While there is described herein a preferred embodiment of the present invention, it is nevertheless to be understood that minor changes may be made therein without departing from the spirit and scope of the invention as claimed.

What I claim as new is:

1. The combination in a printing machine having a frame, a printing roller, and inking rollers including an ink applying roller and an ink spreading roller associated with the ink applying roller, of adjusting means for the ink applying roller and the ink spreading roller, comprising spaced pairs of cooperating guide rails mounted on the frame, a slotted plate slidably supported between each pair of guide rails and adjustably connected with the frame, and said plates forming a bearing for the ink applying roller, a bell crank lever pivoted to each plate, a bearing on each lever set in the slot of the plate and carrying the ink spreading roller, a spring engaging each bearing and plate, and an adjusting rod pivoted to each bell crank lever at one end and supported from the plate at the other end for pivoting the respective bell crank levers to adjust the bearings and ink spreading roller with respect to the ink applying roller.

2. The combination in a printing machine having a frame, a printing roller, and inking rollers including an ink applying roller and an ink spreading roller associated with the ink applying roller, of adjusting means for the ink applying roller and the ink spreading roller, comprising spaced pairs of cooperating guide rails mounted on the frame, a plate having a bifurcated end part forming spaced parallel arms, one of said plates slidably supported between each pair of guide rails, a bar formed with an extension carried on the frame back of each plate, an adjusting member carried by the extension of each bar and connected with the plate adjacent thereto to adjust the same, and said plates forming a bearing for the ink applying roller, a bell crank lever pivoted to each plate, a bearing carried by each lever and disposed between the arms formed by the bifurcated end of its adjacent plate, said latter bearings carrying the ink spreading roller, a spring engaging each bearing and plate, and an adjusting rod pivoted to each bell crank lever at one end and supported from the plate at the other end for pivoting the respective bell crank levers to adjust the bearings and ink spreading roller with respect to the ink applying roller.

GEORGE BABICZ.
